[57] CLAIM

The ornamental design for a finding for an article of jewelry, as shown and described.

DESCRIPTION

FIG. 1 is a front elevational view of a finding for an article of jewelry showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of the fastening member in FIGS. 1-4 and 5 is for illustration purposes only and forms no part of the claimed design.
